INDUSTRIAL THERMOMETER

Paul F. K. Erbguth, Great Neck, N. Y., assignor
to Weston Electrical Instrument Corporation,
Newark, N. J., a corporation of New Jersey

Application November 3, 1950, Serial No. 193,863

20 Claims. (Cl. 73—375)

1

This invention relates to improvements in thermometers and more particularly to a novel construction of the thermometer case including simple means for resiliently supporting the scale plate and for removably mounting the transparent cover plate.

Glass thermometers designed for industry use are provided with metallic protective cases having a transparent glass, or plastic, front and are generally known as industrial thermometers. Numerous problems are associated with such industrial thermometers. It is, of course, necessary that the readable portion of the instrument be exposed to full, open view regardless of the direction or angle at which the temperature-sensitive end of the unit protrudes from the apparatus within which temperature readings are to be taken. This requirement necessitates the use of various special fittings which, in turn, require numerous different types of case designs. In fact, swivel joints are often used for this purpose. In accordance with my invention, a single case design is made to fit a full complement of such special fittings resulting in manufacturing economy.

Present industrial thermometers are of rather complicated construction in that the scale plate must be adjustable with respect to the glass thermometer in order to establish accuracy of indications, and the transparent cover plate must be removable to permit such adjustment in the factory and to afford quick and easy removal of the plate for cleaning purposes and replacement of such plate in the event of breakage. In these respects, a thermometer made in accordance with this invention results in a device which is simple to assemble and which employs a minimum of fastening means such as screws, bolts, etc. The cover glass may be installed and removed without disassembling any part of the case and without the use of tools.

An object of this invention is the provision of an industrial thermometer wherein the protective case is of simple construction and of universal application to fittings of special character.

An object of this invention is the provision of an industrial thermometer having novel means for removably mounting the transparent cover plate.

An object of this invention is the provision of an industrial thermometer case having novel means for adjustably and resiliently supporting a scale plate.

An object of this invention is the provision of an industrial thermometer case in which the means resiliently supporting the scale plate is fixed in position within the case without the use of additional fastening means.

An object of this invention is the provision of an industrial thermometer case wherein the scale

plate is supported resiliently and adjustably by a member that is retained in position by removable spring clips.

An object of this invention is the provision of an industrial thermometer wherein the transparent cover plate is supported in position by a resilient member disposed longitudinally within the case and spring clips disposed transversely within said case.

An object of this invention is the provision of an industrial thermometer comprising a case, a fitting attached to one end of the case, a glass thermometer extending from the fitting into the case, a resilient member disposed within the case, said member including diverging sides spaced on each side of the thermometer, transversely-disposed spring clips within the case, said clips retaining the resilient member in relatively fixed position within the case, a scale plate adjustably secured to each of the diverging sides of the said resilient member, and a transparent cover plate removably disposed between the resilient member, the spring clips and the front of the case.

These and other objects and advantages will be apparent from the following description when taken with the accompanying drawings. The drawings are for purposes of illustration and are not to be construed as defining the scope or limits of the invention, reference being had for the latter purpose to the appended claims.

In the drawings wherein like reference characters denote like parts in the several views:

Figure 1 is a front view of the thermometer case;

Figure 2 is a transverse, sectional view taken along the line A—A of Figure 1;

Figure 3 is an elevation of the lower end of the case;

Figure 4 is a plan view showing a sheet of metal from which the resilient, scale plate-supporting member is formed;

Figure 5 is a plan view showing the completed scale plate-supporting member;

Figure 6 is an end view of the member shown in Figure 5;

Figure 7 is a side view of such member;

Figure 8 is an isometric view of one of the spring clips;

Figure 9 is a plan view of the thermometer case with the resilient scale plate-supporting member in place and showing this member retained in relatively fixed position by clips of the type shown in Figure 8;

Figure 10 is a transverse, sectional view taken along the line B—B of Figure 9 but drawn to an enlarged scale;

Figure 11 is a plan view of the two scale plates;

Figure 12 is an end view of such scale plates;

Figure 13 is an isometric view of a locking unit;

Figure 14 is a partial assembly, in plan, show-

ing one scale plate mounted on the resilient supporting member;

Figure 15 is a cross-sectional view taken along the line C—C of Figure 14;

Figure 16 is a fragmentary, plan view of the thermometer case showing the arrangement for holding the glass thermometer within the case;

Figure 17 is an isometric view showing the two spring clips which, when assembled together, form the arrangement for holding the thermometer in the case;

Figure 18 is an end view showing these two clips assembled together;

Figure 19 is a fragmentary, plan view, showing the upper part of the thermometer case with a 15 5 10 15 20 25 30 35 40 45 50 55 60 65 70 75 80 85 90 95 100 105 110 115 120 125 130 135 140 145 150 155 spring clip 35 is inserted cross-wise into the case it is subject only to sliding movement longitudinally of the case.

Two spring clips, of the type shown in Figure 8, are employed to anchor the resilient member (Figure 5) within the case. The spring clips are inserted, one at each end of the case, and the resilient member, identified by the numeral 40, is inserted into the case so that the offset ends 32 fall within the transverse recesses 22 (see Figure 1). Each of the spring clips is then slid toward the resilient member until it abuts against the end thereof within the clearance provided by the notches 25, 25' (see Figure 7). In such position, as shown by the lower spring clip in Figure 9, the spring clip overlies the end portion of the base 30 of the resilient member. The upper spring clip is likewise moved into the overlying position whereby the resilient member is firmly and securely locked in position with respect to the case. The relative disposition of the parts, in the assembly thus far described, is shown in the enlarged cross-sectional view of Figure 10, taken along the line B—B of Figure 9.

As stated, above, one function of the resilient member 40 is to support the scale plate of the instrument. In accordance with conventional practice, the scale plate consists of two parts 45, 45', as shown in Figure 11. These parts include complementary scale graduations and when mounted in the instrument there is presented the appearance of a single scale plate with graduations extending to either side of the glass thermometer. Each scale plate includes a circular hole 46, 46' located for minimum interference with the scale graduations and numerals, and each scale plate is given a contour as shown in the end view of Figure 12. Specifically, the central portion 48, 48' of each scale plate member is flat, the outer edge 49, (49') is offset with respect thereto, and the inner edge 50, (50') is formed in a reverse bend. As shown in Figure 14, the scale plate 45 is adjustably attached to the wing portion of the resilient member 40 by a screw 51 passing through the hole 46 in the scale plate and into threaded engagement with a nut disposed under the scale plate. The nut 52 employed for this purpose is of the stamped variety as shown in Figure 13. Such nuts are well known and include a clearance hole 53 in one face and a pair of punched, bowed fingers in the other face, said fingers arranged to provide a self-gripping action on a screw threaded therebetween. As shown in the right hand portion of the Figure 14 assembly, the nut 52 is slidably mounted over the edge of the wing member 28' of the resilient member and when the scale plate-fastening screw is threaded into such nut the scale plate and nut may be moved, slidably, within a range defined by the elongated aperture 27'. In prior constructions adjustment of the scale plate position is accomplished by providing an elongated aperture in the scale plate which results in a displacement of the scale plate relative to the fastening screw. In such prior construction the result is not particularly pleasing, the elongated aperture or slot interferes with the placement of the numerals and disrupts the uniformity of the graduations. More importantly, after relatively few adjustments of the scale plate the surface thereof becomes marred by the screw head. In my construction, the screw and scale plate move as a unit, during the mechanical positioning or adjustment of the scale plate and, consequently, the surface quality of the scale plate is not ruined

and, additionally, there are no restrictions placed upon the extent of the scale graduations or the location of relatively large numerals. Still further, the described construction facilitates the assembly operation as it is a simple matter to align the hole in the scale plate with the hole in the nut for insertion of the fastening screw.

Figure 15 is a cross-sectional view taken along the line C—C of the partial assembly shown in Figure 14. It will be noted that the center portion 48 of the scale plate conforms to the width of the wing section 28 and lies substantially flush thereon as the nut 52 is made of relatively thin material. Such design prevents rotation of the scale plate member about an axis formed by the single mounting screw. The offset end section 49 of the scale plate lies in a plane substantially parallel to that of the base portion 30 of the resilient member, while the inner-reverse bend 50 of the scale plate slopes toward the median line of such base portion 30. It will be now apparent that when the two scale plate members are assembled on the resilient member, such scale plates come fairly close together at the base section 30, and the offset side portions 49 (49') of the scale plates provide relatively flat surfaces for the support of a cover glass. In the actual assembly of the device, the resilient member 40 is first secured within the case by the spring clips, after which the two scale plate members are attached as just described.

The arrangement for supporting a glass stem thermometer within the case will now be described. In Figure 17 there are shown a spring clip 55 and a more or less conventional fuse clip 56. The clip 55 is somewhat similar to the spring clip 35 (see Figure 8) and includes the parallel apertures 57 in the base portion thereof. The side arms of the fuse clip 56 are passed through these apertures to form the assembly shown in Figure 18 and the latter is inserted within the case 10 at the upper end thereof, as shown in the fragmentary plan view of Figure 16. The upper portion of the thermometer is disposed within the resilient side arms of the fuse clip, as shown in Figure 25.

Reference is now made to Figure 19 which is a fragmentary, plan view showing the upper portion of the thermometer case. Slidably disposed between the sides 14 of the case 10 is a flat plate 60, the purpose of which is to facilitate insertion and removal of the transparent cover glass, as will be described in detail hereinbelow. The limits of the slidable movement of this plate are shown by the solid and dotted line positions thereof. Such movement of the plate may be accomplished without fear of the plate becoming disassembled from the case by reason of a novel construction now to be described.

Figure 20 illustrates a leaf spring 65 of arcuate shape and having a rivet 66 rigidly secured to the center thereof. The formation of the rivet is better shown in Figure 21 which is a cross-sectional view taken along the line D—D of Figure 20 and drawn to an enlarged scale. Each end of the leaf spring includes a notch 67 designed to fit over the shoulders 68 of the pins 69 that are soldered, welded, or otherwise secured to the end 15 of the case, as shown in the fragmentary view of Figure 23. It will be noted the pins 69 extend along the side walls of the case and lie under, but slightly spaced from, the turned-over case sides 14. The construction of the slidable plate 60 is shown in Figure 22 and includes a backing plate 71 having a transverse,

elongated aperture 72 therein, and a pair of ears 13 that are bent slightly from the plane of the backing plate. These two plates, the upper plate 60 and the backing plate 71 are intimately secured together as by soldering, welding or etc., to form a unitary structure. Alternatively, such structure can be cast as a single unit. In assembling the slideable plate arrangement, the leaf spring 65 is inserted under the case sides 14 with the notches 67 of the spring disposed over the shoulders 68 of the pins 69. In this position the center of the leaf spring and the rivet 66 extend slightly beyond the confines of the case proper. The unitary structure of Figure 22 is then placed over the leaf spring such that the rivet 66 lies in the elongated aperture 72 of the backing plate. By applying a combined tilting motion to the plate 60, in a direction along the longitudinal axis of the case, and a simultaneous rotary motion, first one and then the other of the ears 13 can be forced under the associated case sides 14, while still retaining the rivet 66 within the aperture 72. A clear understanding of this assembly may be had from Figure 24 which is a cross-section view taken along the line E—E of Figure 19. It will be clear that the ends of the leaf spring 65 rest upon the shank portions of the pins 69, to either side of the shoulders 68, and that the leaf spring results in a constant upward pressure exerted by the ears 13 against the bent-over case sides 14. Such pressure is sufficient to retain the plate 60 in position yet affords ready, slideable movement of the plate, longitudinally of the case, within the limits defined by the elongated aperture 72 and the coacting rivet 66.

Figure 25 illustrates a complete industrial thermometer with the transparent cover glass removed and with certain parts broken away for purposes of description. One end of the case 13 has a straight-through type of fitting 80 secured thereto, the latter carrying a coupling nut 81 that is freely rotatable on the stem of the connecting piece 83. The coupling nut permits attachment of the thermometer, by means of a union or a separable socket connection, to a piece of apparatus, as is standard practice in this art. A thin-walled bulb chamber 84 is secured to the connecting piece 83 by a left handed thread to prevent the chamber from loosening if the case is turned in removing the thermometer from the socket. It is also standard practice to provide an asbestos packing 85, uniformly compressed around the enlargement 86 on the stem of the glass thermometer 87, to prevent movement of the thermometer relative to the scale plate. To promote rapid heat transfer, the space between the thermometer and the thin-walled bulb chamber 84 may be filled with mercury, graphite or other good heating conducting medium. As already mentioned, the upper end of the glass thermometer is secured against lateral displacement by the fuse clip 56.

I have already stated that a case made in accordance with this invention is of universal application as it may be attached to a variety of special fittings such as the straight-through, right angle front or back, oblique, etc. types. As shown in Figures 27 and 28, the base of the fitting 80 is shaped to conform to the adjoining case end, shown clearly in Figure 26, and carries the two locating pins 90 that fit into the holes 19 of the case end to assure a proper, accurate assembly. The fitting is attached to the case by means of two screws passing through the mounting holes 91 into threaded engagement with the

threaded holes 18 in the case, the mounting holes in the fitting being counterbored at one end for flush mounting of the screw heads. A hole 92 in the fitting is adapted for alignment with the hole 17 in the case end whereby the glass thermometer passes readily therethrough. As a practical matter, the hole 92 in the fitting can be substantially larger than the hole 17 in the case to eliminate the need for critical alignment of these holes in the assembled device. Although I have specifically described a straight-through type of fitting it will be understood that right angle and oblique fittings can be furnished each having a base conforming to the shape of the case end and each provided with mounting holes, a thermometer hole and locating pins, located and disposed as described with reference to Figure 27. Consequently, any such fitting may be attached to the case conveniently, quickly and properly to produce an industrial thermometer designed for a particular application.

The removal of the cover glass from the above described thermometer case will now be described. Figure 29 is a front view of the case 10 with the cover glass 100 in place and Figure 30 is a transverse, sectional view taken along the line F—F of Figure 29 and drawn to an enlarged scale. It will be noted that the cover glass is disposed between the bent-over ends 37 of the spring clips 35 and rests upon the substantially-flat surface formed by the offset ends 49, 49', of the two scale plates. The glass is pressed upward, by the pressure provided by the wings 28, 28', of the resilient member 40, against the under surface of the case sides 14 and the offset portion 20 of the case end. Consequently, the cover glass is held firmly, but resiliently, in place and will not rattle or shatter when mounted on machinery which has a tendency to vibrate. To remove the glass, the slideable plate 60 is moved to the position shown in Figure 31 and by means of a gentle pressure and sliding action the glass is moved in the direction of the plate 60 so that the lower edge 101 of the cover glass clears the inner edge 20 of the case end. In this position the glass is held within the case only by the overlying case sides 14. Finger pressure is now applied at one side of the glass, as indicated by the arrow a, in Figure 30. The glass is pressed downward, against the spring tension of the wing 28 of the resilient member, until the edge of the glass lies below the end 37 of the spring clip, whereupon the glass may be moved laterally to abut against the side 36 of the spring clip, as shown in Figure 32. When the finger pressure is now removed, the opposite side of the cover glass lies clear of the case side 14 and will move outwardly of the case (as indicated by the arrow, Figure 32) in response to the spring pressure of the wing 28'. It is to be noted that the free edge of the wing member 28 lies outside of the inner edge of the case side 14. Consequently, the edge of the case side, in contact with the glass, serves as a fulcrum about which the cover glass rotates in response to upward pressure exerted by the wing member at a point displaced from such fulcrum. As is apparent from Figure 33, the glass may now be removed by simply withdrawing same laterally from the case.

To mount the cover glass in position a reverse procedure is followed. Briefly, the side of the glass is inserted within one side of the case with the inner edge thereof under the bent-over end of the spring clip (Figure 32). By finger pres-

sure, the opposite side of the glass is pressed down against the tension of the wing member 28' (Figure 32) and then moved sideways until the first side of the glass clears the overlying end 37 whereupon the glass lies between the opposed ends 37. Release of the finger pressure results in the upper surface of the glass abutting the case sides 14 (Figure 31). It may be well to point out at this point that the width of the cover glass is slightly less than the distance between the opposed ends 37 of the spring clip 35 and, therefore, from a practical standpoint, the described arrangement provides a self-centering of the cover glass. Should one or the other sides of the glass lie under the adjacent off-set end of the spring clip this fact is immediately apparent by the non-level disposition of the glass and the space between the glass surface and the case side. As a practical matter, when the cover glass is moved laterally, upon insertion into the case, a gradual decrease in the applied finger pressure results in a distinctly audible "click" as the edge of the glass clears the overlying end of the spring clip and contacts the adjacent side 14 of the case. Once the glass is centered laterally in the case it is moved down into final position and the slideable plate 60 returned to the position shown in Figure 29.

In the above description of the removal and insertion of the cover glass I mentioned a single spring clip but it will be understood the thermometer case includes two such clips spaced at either end of the resilient member 40 that provides the resilient holding of the cover glass against the overlying sides of the case, see Figure 9.

Reference is again made to Figure 30. I have previously stated that the resilient member 40 is made of a single sheet of spring material bent to provide the diverging wing members 28, 28', joined by a central channel portion. The lines along which the bends are made to form the channel portion bisect a series of elongated apertures (see Figures 4 and 5). Consequently, when a force is applied to one of the wing members as, for example, to the member 28 in the direction of the arrow *a*, in Figure 30, this side of the resilient member flexes at the axis *x* rather than the axis *y*. Thus, there occurs a minimum, counter-clockwise movement of the end of the scale plate lying under the glass thermometer 31 and there is no danger of disturbing or injuring the thermometer upon a flexing of one or both of the wing members 28, 28'. It may here be pointed out that two, or more, resilient members 40 can be used when the thermometer case is relatively long, say exceeding 12 inches.

Having now described my invention in detail in accordance with the patent statutes, various changes and modifications will suggest themselves to those skilled in this art, and it is intended that such changes and modifications shall fall within the spirit and scope of the invention as recited in the following claims.

I claim:

1. A thermometer case comprising a body having inturned sides forming an outer bearing surface for a transparent closure plate, a pair of spring clips laterally-disposed within and spanning the body, said clips having inturned ends diverging from the inner surface of the inturned body sides, a transparent closure plate removably disposed in said body and having edge portions positioned between the inturned ends of the spring clips and abutting said bearing

surface, and a resilient member extending longitudinally within the body, said resilient member having divergently-extending wing members resiliently urging the said closure plate against the inner surface of the inturned body sides.

2. The invention as recited in claim 1, wherein the said resilient member is retained in relatively fixed position within the body by the said spring clips.

3. The invention as recited in claim 1, wherein the resilient member is formed from a single sheet of material and said wing members are joined by a central channel portion.

4. The invention as recited in claim 3 and including apertures in the sheet material, said apertures lying on the lines defining the base of said channel portion.

5. A thermometer case comprising a body member having inturned sides forming an outer bearing surface for a transparent closure plate; a pair of spaced recesses in the bottom of the body member; a resilient member longitudinally disposed within the body member, said resilient member having divergently-extending wings extending toward each inturned side of the body member, and a flat base portion having offset ends disposed within the recesses in the bottom of the said body member; spring clips overlying the offset ends of the resilient member, said spring clips conforming substantially to the transverse contour of the body member and terminating in offset ends diverging from the inturned sides of the said body member; and a transparent closure plate resiliently sustained between the inturned sides of the body member and the wings of the said resilient member, said closure plate having sides spaced from the offset ends of said spring clips and abutting said outer bearing surface of the inturned sides.

6. The invention as recited in claim 5, including a solid plate closing one end of the said body member; and an apertured plate closing the other end of said body member, said apertured plate having one side offset at substantially a right angle and such offset side lies substantially flush with the inturned sides of the body member.

7. The invention as recited in claim 5, including a slideable plate disposed between the inturned sides of the body member, said slideable plate movable longitudinally with respect to the body member.

8. The invention as recited in claim 7, including means limiting the extent of the normal slideable movement of the said slideable plate.

9. The invention as recited in claim 5, including a pair of calibrated scale plates; and means adjustably mounting each scale plate on a wing of the resilient member.

10. The invention as recited in claim 9, wherein the means adjustably mounting each scale plate on the associated wing comprises an elongated aperture in the wing, a nut slidably carried by the wing, a hole in the scale plate, and a screw passing through the hole in the scale plate and the elongated aperture in the wing into threaded engagement with the said nut.

11. A thermometer case comprising a body having inturned sides forming an outer bearing for a transparent closure glass; an end plate closing each end of the body; a pair of spaced recesses in the bottom of the body; a resilient member having divergently-extending wings directed toward the inturned sides of the body,

and a flat base portion having offset ends disposed within the said recesses; a pair of spring clips each overlying the offset ends of the base of the resilient member, said spring clips conforming substantially to the transverse contour of the body and terminating in offset ends diverging from the inturned sides of the said body; a transparent closure plate disposed between the offset ends of the spring clips and resiliently sustained between the inturned sides of the body and the wings of the resilient member; a slideable plate disposed between the inturned sides of the body and at one end thereof; opposed ears extending from the plate and slideable under the inturned sides of the body; an elongated slot in the bottom of the slideable plate; a pin; and spring means resiliently retaining the said pin in the said elongated slot.

12. The invention as recited in claim 11, wherein the spring means resiliently retaining the said pin in the elongated slot comprises an arcuate leaf spring having a notch at each end, and said leaf spring is supported by pin members having a shoulder disposed within the said notches.

13. The invention as recited in claim 12, wherein the pin members are spaced from the bottom of the body and are secured to one of the end plates.

14. A thermometer case and assembly comprising a body having inturned sides forming an outer bearing for a transparent closure plate; end plates closing each end of the body; a resilient member disposed in the body, said resilient member having diverging wings joined by a central channel portion; spring clips removably retaining the resilient member in place within the body, said spring clips conforming to the transverse contour of the body and terminating in offset ends diverging from the inturned sides of the body; a transparent closure plate disposed between the offset ends of the said spring clips and compressively urged against the said inturned sides of the body by spring pressure resulting from a flexing of the said wings of the resilient member; a slideable plate disposed between the inturned sides of the body and at one end thereof; and a pair of scale plates adjustably mounted on the said wings, said scale plates each having an outer marginal side in substantially flush contact with the inner surface of the transparent closure plate and an inner marginal side disposed within the channel portion of the resilient member.

15. A sub-assembly for industrial thermometers and comprising a resilient member having divergently-extending wing portions joined by a central channel portion, a longitudinally-extending slot in each wing portion, a nut slidably carried by each wing portion, a scale plate disposed over each wing portion, a hole in each scale plate, a screw passing through the scale plate hole and the cooperating wing slot into threaded engagement with the associated nut, each scale plate having an inner marginal side formed in a reverse bend and lying within the said channel portion and an outer marginal side angularly offset with respect to the center section of the scale plate and lying in a common plane.

16. The invention as recited in claim 15, including apertures in the said resilient member, said apertures lying on the lines defining the base of the said channel portion.

17. In an industrial thermometer of the type comprising a case having a removable transparent cover plate, threaded fitting secured to an end of the case, and a glass thermometer extending through the fitting into the case, the improvement comprising a base portion on the fitting, said base portion conforming to the general configuration of the case end, a set of locating pins extending from the base portion of the fitting into the said locating holes, a set of holes in the case end, correspondingly-aligned holes passing through the base portion of the fitting, fastening screws passing through the holes in the fitting and threaded into the holes in the case end, and a central aperture in the base portion of the fitting and aligned with an aperture in the case end, said aligned apertures providing a passageway for the glass thermometer.

18. An industrial thermometer comprising a case having inturned sides forming an outer bearing for a transparent closure plate; a resilient member supported on the bottom of the case, said resilient member having divergently-extending wing portions joined by a central channel portion; a pair of spring clips removably securing the resilient member within the case, said spring clips conforming to the transverse contour of the case and having offset ends diverging from the inturned sides of the case; a scale plate member adjustably mounted on each of the said wing portions, said scale plates each having an offset marginal side lying in a plane substantially parallel to that of the inturned sides of the case; a transparent closure plate resiliently sustained between the inner surfaces of the said inturned sides of the case and the said offset marginal sides of the scale plates, said closure plate disposed between the offset ends of the said spring clips; a removable fitting secured to one end of the said case; aligned holes in the fitting and the adjacent case end; a glass thermometer passing through such aligned holes and lying within the channel portion of the said resilient member; a slideable plate disposed between and substantially flush with the inturned sides of the case; and means normally effective to limit the extent of the slideable motion of said slideable plate.

19. The invention as recited in claim 18, wherein the case end to which the removable fitting is secured has an offset side that is co-planar with the inturned sides of the case and partially overlies the transparent closure plate.

20. The invention as recited in claim 19, wherein the adjustable mounting of the scale plates on the wing portions comprises an elongated slot in the wing portion, a nut slidably carried by the wing portion, a hole in the scale plate, and a screw passing through the hole in the scale plate and the slot in the wing portion into threaded engagement with the nut.

PAUL F. K. ERBGUTH.
